Primary Examiner — Robert M Spear*Assistant Examiner* — Darcey E Heflin(74) *Attorney, Agent, or Firm* — Koppel, Patrick, Heybl & Philpott(57) **CLAIM**

The ornamental design for a bag closure, as shown and described.

DESCRIPTION

FIG. 1 is a top, front, left side perspective view of an embodiment of a bag closure incorporating features of the present invention.

FIG. 2 is a front elevation view of FIG. 1.

FIG. 3 is a right side elevation view of FIG. 1.

FIG. 4 is a left side elevation view of FIG. 1.

FIG. 5 is a rear elevation view of FIG. 1.

FIG. 6 is a top plan view of FIG. 1.

FIG. 7 is a bottom plan view of FIG. 1; and,

FIG. 8 is a cross-sectional view taken along line 8-8 of FIG. 3 of the embodiment of FIG. 1.

The broken lines shown in the above figures depict environmental subject matter only and form no part of the claimed design in those embodiments.
